EXTENSIBLE TABLE

Patrice A. Arsenault, Mexico, Maine

Application November 22, 1932
Serial No. 643,938

1 Claim. (Cl. 45—114)

This invention relates to the broad class of furniture and has more specific reference to an extensible table.

Briefly stated, the desired results are accomplished by providing a leg supported frame wherein the side rails of the frame are extensibly connected together and especially fashioned to provide storage receptacle or pockets for a flexible receding top section which is joined to one of the main rigid top sections to operate in conjunction therewith.

More explicitly stated, the novelty is predicated upon a special flexible extensible and retractable intermediate top section which is permanently attached to the complementary rigid top section in order that it may be readily moved to and from its useful position.

Other features and advantages will become more readily apparent from the following description and drawings:

In the drawings:

Figure 1 is a top plan view of a table constructed in accordance with the inventive conception involved herein showing the table collapsed into its normal state.

Figure 2 is a view similar to Figure 1 showing the table extended, that is, with the intermediate flexible receding section in position for use.

Figure 3 is a top plan view of the frame with the top, as a unit, removed.

Figure 4 is a side view of Figure 1.

Figure 5 is a side view of Figure 2.

Figures 6 and 7 are detail perspective views.

Figures 8 and 9 are transverse sections.

Figure 10 is a fragmentary longitudinal sectional view through the table top, and particularly through the slatted flexible section thereof.

Referring now to the drawings and particularly to Figure 2, it will be observed that one of the rigid sections of the top is distinguished by the numeral 11 while the companion section is denoted by the numeral 12 and the receding flexible intermediate section by the numeral 13. The latter section is composed of a plurality of transverse abutting slats 14 jointed together by tongue and groove joints to permit relative movement of the slats to allow for extension and retraction.

As seen in Figure 10, the slats are maintained in assembled flexible jointed relationship through the medium of flexible tie cords or wires 14, the wires being anchored at one end as indicated at 15 to the top section 12. The opposite end of the wire is provided with a washer 16 cooperable with a coiled cushioning and retention spring 17 located in the socket in the free end slat.

The legs, which may be of any appropriate construction, are denoted by the numerals 18 and are joined together by end bars 19. As shown in Figures 6 and 7, the side rails are composed of slidably connected sections, one section being denoted by the numeral 20 and the other by the numeral 21. These are formed with complementary grooves 22 and 23 which function as keyways for a key strip 24 which is located in the grooves and permanently fastened to the section 20 in the groove 23. The section 20 is formed with a slot 25 cooperating with a reduced terminal end portion 26 on the section 21. Both of the sections 20 and 21 are provided with bevelled surfaces 27 and 28 formed to match with each other when the table is collapsed as shown in Figures 1 and 4. These bevelled surfaces 27 and 28 form entrance means to the "pocket". The "pocket" is made up of the slot 25 cooperating with the extended terminal 26, thereby forming a keeper for the collapsible and retractile top section 13.

The gist of the invention is in the provision of a leg supported frame embodying the extensible side rails composed of the complementary sections 20 and 21 wherein such sections are formed to define longitudinally elongated pockets for the reception of the longitudinal edge portions of the collapsible extensible and retractile table top section 13. Particular emphasis is placed on the fact that this section 13 is permanently attached to the section 21 so that it functions as a follower. In other words it moves in conjunction with said section 12. The section 13 has two definite positions, namely, the concealed retracted or reeding position shown in Figure 5. When in the latter position it takes the place of the table leaves (not shown) which are usually made as separate parts of the table top.

It is evident that the collapsible table top section 13 functions somewhat in the manner of the cover to a roll top desk. By using tongue and groove slats, dependable joints are assured. Also by tying the slats together, a positive rigid assembly is maintained. Moreover, by incorporating the cushioning and shock absorbing springs, said springs compensate for the indefinable relative angling of the slats as they are moved from storage or retracted position to extended using position.

The main idea is in the permanent attachment of the slatted table top section to the relatively movable table top section 12, together with the means underlying the remaining section 11 which

permits such section 13 to be moved to a concealed, out-of-the-way or retracted position when not in use.

It is thought that persons skilled in the art to which the invention relates will be able to obtain a clear understanding of the invention after considering the description in connection with the drawings. Therefore, a more lengthy description is regarded as unnecessary.

10 Minor changes in shape, size, and rearrangement of details coming within the field of invention claimed may be resorted to in actual practice, if desired.

What is claimed is:

- 15 A table of the class described comprising two pairs of legs, a pair of side members, each having its outer end connected to a leg of each pair, each side member having a longitudinally extending slot therein adjacent its upper edge and 20 extending from the leg end of the member an appreciable distance toward the other end of the member, said member having a diagonally arranged slot therein extending from its upper edge to the inner end of the first mentioned slot, 25 a pair of second side members connected to the opposite legs and each having its inner end part

reduced, with the upper edge of the reduced part being in horizontal alignment with the lower wall of the longitudinal slot in the first mentioned side member when the two side members are in fully overlapping relation, the junction of the reduced part of the second side member with the other part thereof forming a sloping shoulder which is in alignment with a sloping wall of the notch when the two side members are in said mentioned position, the abutting faces of the two sets of side members having grooves therein, a strip located in the grooves and fastened to one of the side members, a pair of rigid top sections fastened to the upper edges of the outer end parts of the two sets of side members and extending over the legs, a flexible section connected to the inner end of one rigid section and adapted to pass through the notches into the longitudinal slots when the table parts are moved toward each other, said flexible section moving out of the slots and notches upon the wide portions of those side members which have their inner end portions reduced, whereby said flexible section will lie between the rigid sections with the top flush with the tops of said rigid sections.
